EDWARD LEICHTER, OF NEVADA CITY, CALIFORNIA, ASSIGNOR OF ONE-FOURTH TO JOHN BENDER, OF HAMILTON, OHIO, AND ONE-FOURTH TO J. C. CAMPBELL, OF NEVADA CITY, CALIFORNIA.

ROCK-DRILL.

No. 823,059.

Specification of Letters Patent.

Patented June 12, 1906.

Application filed May 29, 1905. Serial No. 261,294.

To all whom it may concern:

Be it known that I, EDWARD LEICHTER, a citizen of the United States, residing at Nevada City, Nevada County, California, (post-office address Nevada City, California,) have invented certain new and useful improvements in Rock-Drills, of which the following is a specification.

This invention, pertaining to improvements in rock-drills operated by fluid-pressure, will be readily understood from the following description, taken in connection with the accompanying drawings, in which—

Figure 1 is a longitudinal section of a rock-drill exemplifying my invention; Fig. 2, a similar view at the chuck end of the machine in an enlarged scale, and Fig. 3 a transverse section in a compound plane at the chuck.

In the drawings, 1 indicates a cylindrical shell having a cylindrical bore; 2, a thread upon the exterior of the shell; 3, the rear head for the shell, this head forming also a rear cylinder-head for the machine; 4, a cap screwed upon the rear end of the shell by means of an interiorly-screw-threaded ring 4^a and securing the rear head in place, this cap having a rearwardly-extending cylindrical shank; 5, a T-piece swiveled upon the shank of the cap and adapted to have connected with it the inlet-tube for the actuating fluid; 6, the supporting-clamp for the machine, the same being internally threaded to engage the threads of the shell, so that by turning the shell the general device may be advanced with reference to the clamp; 7, a crank secured upon the rear end of the shank of the shell-cap, whereby the threaded shell may be turned in the nut formed by the clamp; 8, a distributing-chamber within the shell-head 3; 9, an axial passage in the shank of the shell-cap leading rearwardly from the distributing-chamber 8 and turning at right angles through the wall of the shank, where it is engaged by the T-piece; 10, inlet-passage 45 in the T-piece, always in communication with the passage 9; 11, the cylinder, separably inserted within the shell and having its rear end closed by shell-head 3; 12, a chuck-body having its rear portion fitting within the bore of the shell and impinging against the forward end of the cylinder 11, the extreme forward portion of this chuck-body

projecting outwardly beyond the front end of the shell; 13, a bushing screwed solidly into the front end of the shell and forming a bearing for the chuck-body at the forward end of the shell; 14, keys carried by the chuck-body where it fits within the bushing 13, these keys engaging keyways in the bushing, so that the chuck-body may reciprocate but not turn relative to the bushing and shell; 15, a cushion-ring—say of rubber—disposed around the chuck-body and engaging between the rear face of the bushing and a forwardly-presenting shoulder upon the chuck-body; 16, the shank of the drill separably engaging a bore in the nose of the chuck-body; 17, the piston arranged for reciprocation in the cylinder; 18, the striking portion of the piston, being its forward end, adapted to strike upon the rear end of the drill-shank; 19, an annular rib within the cylinder fitting upon the body of the piston, this rib being termed the "exhaust-rib;" 20, an enlarged cylindrical head upon the rear end of the piston; 21, an annular rib upon the interior of the cylinder engaging the enlarged head of the piston, this rib being termed the "back-cushion" rib; 22, an annular rib upon the interior of the cylinder between the ribs 19 and 21 and fitting the enlarged head of the piston, this rib being termed the "front-cushion" rib; 23, an annular rib upon the interior of the cylinder at its forward end adapted to fit the main cylindrical portion of the piston, 85 this rib being longitudinally grooved, so that when the body of the piston is disposed within the rib the grooves will furnish passages for the fluid, this rib being termed the "vibration-rib;" 24, ports at the front end of 90 passages leading from the distributing-chamber 8 and admitting the supply fluid at all times to the cylinder at a point between ribs 22 and 19; 25, exhaust-port leading from the interior of the cylinder outwardly through the chuck-body; 26, ports in the main body of the piston at about the middle of its length and leading from the rear end of the cylinder through a passage or cavity formed in the piston; 27, similar ports in the enlarged rear 95 head of the piston; 28, flattened sides of the drill-shank where the shank engages within the bore of the chuck-body; 29, chuck-jaws sliding radially in mortises in the nose of the

chuck-body, their inner faces engaging the flattened sides of the drill-shank, their outer faces being normally flush with the periphery of the nose of the chuck-body; 30, a chuck-ring turning upon the nose of the chuck-body; 31, recesses or relief portions in the bore of the chuck-ring adapted when brought opposite the chuck-jaws to permit the chuck-jaws to move outwardly a sufficient distance to 10 clear the cylindrical portion of the drill-shank; and 32, a spring-pin radially disposed in the chuck-ring, its point engaging a segmental groove in the nose of the chuck-body, each end of this groove being deepened to receive the point of the pin.

The chuck-ring may be turned by the hand, so that either its plain-bore portion or its grooved-bore portions are opposite the chuck-jaws. The deepened portions at the 20 ends of the groove engaged by the spring-pin serve to yieldingly lock the chuck-ring in position with its plain-bore portions opposite the chuck-jaws. When the plain portions of the chuck-ring are opposite the jaws, 25 then the jaws are held inwardly and properly hold the shank of the drill. By turning the chuck-ring the jaws are permitted to move outwardly and release the drill.

The drill is fed to its work by turning the 30 shell within its clamp by means of the crank 7, and it is manifest that as the drill turns with the shell its rotation and advance will be always in harmony, independent of the nature of the material it operates upon. The 35 keys 14 compel the chuck and drill to turn with the shell, but permit of the chuck and drill reciprocating to some degree, the cushion-ring 15 holding these parts in normal rearward position, but yielding to some degree in a forward direction. The ports 24 and the longitudinal grooves furnishing passages to them and also the ports 26 and 27 and the port 25 are to be in sufficient number to provide for the flow of the fluid with 45 proper freedom.

The fluid under pressure reaches the rear end of the cylinder through ports 24 and 26 and produces the first portion of the forward stroke of the piston. The advance of the 50 piston causes ports 26 to be closed by cylinder-rib 19, whereupon the fluid from ports 24 reaches the rear end of the cylinder through the medium of ports 27, which have become uncovered. When in the advance of the 55 piston ports 27 shall have become closed by cylinder-rib 22, then the supply of fluid behind the piston becomes entirely cut off and the piston completes its stroke and delivers its blow upon the drill by momentum. While 60 the piston is thus delivering its blow by momentum, it becomes cushioned by the resistance of the fluid temporarily confined in the forward interior portion of the chuck-body upon the forward annulus of the enlarged head of the piston, the effect of this

pressure after the piston has delivered its blow being to throw the piston upon its rearward or return stroke until the ports 27 are closed by rib 21, which brings the piston to rest for the next forward stroke. The 70 exhaust of the fluid occurs when ports 26 pass forward of rib 19, the fluid then passing through the grooves in vibration-rib 23 and thence out at port 25. At the time the piston is delivering its blow and is most subject to vibration liable to produce damaging wear upon the parts it is guided and steadied by the vibration-rib 23, which it engages at that time, the portion of the piston engaging the bore of this rib being practically surrounded 75 by the fluid passing through the grooves in the vibration-rib.

The form of the piston is such that while it has the liberality of length important in nice fitting and maintenance has the bulk of its 80 weight concentrated at its forward end by reason of its rearward cavity, thus freeing the rearward portions of the piston very largely from the vibratory effects incident to the striking of the blow. The arrangement of 85 the cylinder-ribs in relation to the hammer is such as to secure a satisfactory degree of 90 boring at all times.

It is to be observed that there are no heavy reciprocating parts, that the action of the piston upon the drill-shank is substantially identical with that of the miner striking a drill with a hand-hammer; that there are no valves to cut and leak; that any leakage past the piston, which acts as its own valve, finds 95 its way to the exhaust without material impairment of the force of the blow; that the construction permits of a very material reduction in weight as compared with known machines of the same capacity; that the 100 chuck is adapted for drills formed of the ordinary steel of the market; that no damage can result from feeding too fast or too slow as the piston becomes cushioned at each end of its extreme stroke; that the rotation and advance of the drill remains in harmony regardless of variation in material being drilled; that the removal of the shell-cap permits the 105 removal of all of the interior parts; that the distribution of fluid is such as to bring about 110 a remarkable economy in operation; that ratchets, gibs, rockers, spring-pawls, piston-rings, nuts, rods, yokes, &c., are dispensed with, and that the machine notwithstanding 115 its peculiar efficiency is of special simplicity 120 and accomplishes with ten members what in known constructions has required from fifty to sixty members.

While the improvements have been specially designed with reference to and have been 125 set forth as finding exemplification in a rock-drill, it will at once be recognized by those skilled in the art that a number of the novel features are applicable to fluid-operated tools generally, and it is therefore to be understood 130

that notwithstanding the exemplification which has been chosen the claims thereto are not limited specifically to tools for drilling rock or other material.

5 I claim as my invention—

1. In a rock-drill, the combination, substantially as set forth, of a shell, means for turning and advancing said shell, a cylinder within the shell, a fluid-actuated piston reciprocating within the cylinder, a chuck-body separably disposed within the forward end of the shell and having a chambered portion within the shell, and a bushing secured in the forward end of the shell and serving to retain 15 the chuck-body therein.
2. In a rock-drill, the combination, substantially as set forth, of a shell, means for turning and advancing said shell, a separate cylinder within the shell, a fluid-actuated piston reciprocating within the cylinder, a chuck-body separably disposed within the forward end of the shell, and a bushing secured in the forward end of the shell and serving to retain the chuck-body therein. 20
3. In a rock-drill, the combination, substantially as set forth, of a shell, means for turning and advancing said shell, a cylinder within the shell, a fluid-actuated piston reciprocating within the cylinder, an exteriorly-shouldered chuck-body separably disposed 25 within the forward end of the shell, having a chambered portion within the shell, and abutting against the forward end of the cylinder, a bushing secured in the forward end of the shell, and a cushion-ring disposed between 30 shell, and a cushion-ring disposed between 35

said bushing and the shoulder of the chuck-body.

4. In a rock-drill, the combination, substantially as set forth, of a shell, means for turning and advancing said shell, a cylinder 40 within the shell, a fluid-actuated piston reciprocating within the cylinder, an exteriorly-shouldered chuck-body separably disposed within the forward end of the shell and abutting against the forward end of the cylinder, 45 a bushing secured in the forward end of the shell, a cushion-ring disposed between said bushing and the shoulder of the chuck-body, and keys engaging the bushing and chuck-body and adapted to permit reciprocation 50 and prevent rotation of the chuck-body and bushing relative to each other.

5. The combination of an outer shell having an exterior screw-thread and a uniform cylindrical bore; a separate cylinder fitting 55 within the shell and having its rear end flush with the rear end of said shell; a cylinder-head serving to close the rear end of said cylinder and having a flange resting against the rear ends of the cylinder and shell; a cap 60 bearing against the flange of the cylinder-head; and an interiorly-threaded ring engaging screw-threads on said cap and said shell and serving to secure the parts described in position.
